QUENCH BLOCK

Julius Harasty, Westfield, N. J.

Application March 9, 1951, Serial No. 214,777

23 Claims. (Cl. 266—3)

1

This invention relates to a quench block and more particularly to a quench block for use in tempering steel strip, such as razor blade stock. The steel strip is continuously heat treated by passing it from a reel through a degreaser and then over tension rolls into a hardening furnace where the temperature of the steel is raised above the critical temperature. The heat treated strip is then passed through a quench block where its temperature is quickly lowered to approximately room temperature, after which it passes to a draw furnace where it is heated to a temperature below the critical temperature so as to temper the martensite formed in the original operation. From the draw furnace the strip passes through a cooling block to draw rolls and thence to a reel where it is rewound into coils. The quench blocks used previous to my invention were not satisfactory in that they fail to properly quench the steel. In some instances the strip was scratched due to contact with part of the quench block. In many instances the strip cools unevenly, thus causing "sweep" or curvature of the strip, deformation of strip and nonuniform hardening. In some cases the strip does not enter the hardening zone of the quench block in accurate alignment with the muffle tube of the furnace, this also resulting in "sweep." Because of these defects a large percentage of the tempered steel stock was rejected with rejections running as high as 30%.

It is therefore an object of my invention to provide a quench block which will quench a steel strip uniformly.

Another object is to provide such a quench block which will substantially eliminate scratches and bends in the strip.

These and other objects will be more apparent after referring to the following specification and attached drawings, in which:

Figure 1 is a top plan view of the quench block attached to the furnace;

Figure 2 is a side elevation of Figure 1;

Figure 3 is an enlarged side view, partly in section, showing the entry guide;

Figure 4 is an end view, partly in section, of the guide of Figure 3;

Figure 5 is a top plan view of the quench block;

Figure 6 is a side elevation of Figure 5;

Figure 7 is an end view taken in the direction of the arrow 7 of Figure 6;

Figure 8 is a sectional view taken on the line VIII—VIII of Figure 5;

Figure 9 is a sectional view taken on the line IX—IX of Figure 6;

2

Figure 10 is a sectional view taken on the line X—X of Figure 6;

Figure 11 is a schematic view of the cooling system for the quench block;

Figure 12 is a sectional view, similar to Figure 8, showing a slight modification of my device;

Figure 13 is a sectional view taken on the line XIII—XIII of Figure 12; and

Figure 14 is a perspective view of a guide block 10 of Figure 12.

Referring more particularly to Figures 1 and 2 of the drawings, the reference numeral 2 indicates a hardening furnace having a muffle tube 4 therein through which the strip S being heat treated passes. The muffle tube 4 extends a short distance from the exit end of the furnace. A shelf 6 is attached to the exit end of the hardening furnace a short distance below the muffle tube 4. A clamping bracket 8 is fastened to the shelf 6 by means of bolts 10. The elevation of the clamping bracket may be adjusted in any suitable manner such as by providing shims between the shelf 6 and bracket 8. The clamping bracket is U-shaped in cross section with upwardly extending longitudinal flanges 12. A pair of knurled screws 14 are threaded through each of the flanges 12 for the purpose of adjusting the horizontal position of the quench block.

As best shown in Figures 5 to 10, the quench block consists of a lower block 16 and an upper block 18. The lower block 16 has a longitudinal channel 20 in its top surface and has longitudinal side plates 22 fastened to the sides thereof with the tops extending above the top of the lower block. The exit end of the lower block 16 has an end plate 24 fastened thereto. The end plate 24 has two lugs 26 extending upwardly above the top of the lower block 16. As best shown in Figures 8 and 9, three plates 28, 29 and 30, made of tungsten carbide or a similar hard wearing material, are arranged side by side in the channel 20 at the entry end thereof. The middle tungsten carbide plate 29 is of less thickness than the outer tungsten carbide plates 28 and 30. The plates 28 and 30 are identical. A steel filler 32 and shims 34 are arranged on each side of the plates 28 and 30 for holding the plates 28, 29 and 30 in centered position. The width of plate 29 is slightly greater than that of the strip S. Tungsten carbide blocks 36 are arranged in the channel 20 adjacent the entry tungsten carbide blocks and extend the remaining length thereof. The number of blocks 36 is not important, it only being necessary that the channel be filled with tungsten carbide having a thickness slightly greater than that of plate 29. Steel spacers 38

having a thickness substantially equal to the thickness of the strip S may be provided at the four corners of each of the tungsten carbide blocks 36 as shown in Figure 5. An upper tungsten carbide plate 40 is mounted above plate 29 between the tungsten carbide plates 28 and 30. The thickness of the plate 40 is such that it will extend above the top of the plates 28 and 30 when a strip S is between the plates 29 and 40. Tungsten carbide plates 42 of the same size and shape as the plates 36 are mounted above the plates 36. The upper block 18 rests on the plates 42 between the side plates 22. Longitudinal movement of the upper block 18 and the tungsten carbide plates is prevented by the lugs 26. The thickness of each plate 28 and 30 is slightly less than the total thickness of plates 29 and 40 plus the thickness of the steel strip S. Plates 29 and 40 are slightly thinner than plates 36 and 42 so that the upper block 18 does not bear on plate 40, this preventing the strip from being scratched before it becomes hard and also preventing too rapid cooling as the strip enters the quench block. The lower block 16 has a plurality of drilled water passageways 44 extending longitudinally therethrough. Plugs 46 are threaded into each end of each passageway 44. Manifolds 48 and 50 are provided one at each end of the lower block so as to connect the passageways 44. The upper block 18 is provided with similar longitudinal passageways 52 having their ends closed with plugs 54. Manifolds 56 and 58 are provided one at each end of the block for connecting the passageways 52.

As shown in Figures 1 to 3, the lower half 60 of the entry guide is fastened to the entry end of the lower block 16 by means of bolts 62 which are threaded into tapped holes in the bottom block. The lower half 60 of the guide is provided with downwardly extending flanges with an opening therebetween so that the cap screws 62 do not have to extend completely through the guide. The top part of the bottom entry guide 60 is provided with a pair of spaced apart longitudinal slots 64 in which are received two tungsten carbide plates 66 which extend above the top of the bottom part of the guide. The upper part 68 of the guide is provided with similar longitudinal slots 70 for receiving the tungsten carbide plates 66. Asbestos 72 is packed between the end of the furnace 2 and the entrance end of the entrance guide around the muffle tube 4 and also in the joint between the two parts of the guide to prevent loss of neutral atmosphere gas from the furnace. Since the entrance gas in the muffle tube is under a low positive pressure it passes slowly and continuously from the muffle tube through the entrance guide and quench block and escapes through the exit end of the quench block.

Water for cooling the quench block is supplied to the manifolds 48 and 56 at the exit end of the quench blocks through a supply line 74. A pipe 76 with a valve 78 thereon has one end connected to the manifold 48 and the other end connected by means of a flexible hose 80 to supply line 74. A pipe 82 having a valve 84 thereon has one end connected to the manifold 56 and the other end connected by means of a flexible hose 86 to supply line 74. A centrifugal pump 88 delivers water to a surge tank 90 which in turn delivers it to the supply line 74. A bleed-off 92 is provided for removing entrapped air from the cooling water. The pump 88 supplies water under a pressure of between approximately

15 and 40 pounds per square inch depending upon the size of the block and mass of the strip being quenched, thus causing the water to flow through the quench block. The water from the lower block 16 passes through the manifold 50 to a pipe 94 having a valve 96 therein and thence through a flexible hose 98 to the return line 100 which returns the water to a supply tank 102. The suction end of the pump 88 is connected to the tank 102 through a pipe line 104. Water from the upper block 18 passes through a pipe 106 connected to the manifold 56. The pipe 106 has a valve 108 therein and is connected to the return line 100 by means of a flexible hose 110. Thus separate streams of cooling water are caused to flow from the manifolds 48 and 56 in the exit ends of the lower and upper blocks respectively through the several passageways 44 and 52, all arranged substantially in parallel and uniformly across the width of the lower and upper quench blocks respectively and into the manifolds 50 and 58 in the entrance ends of the lower and upper quench blocks. This arrangement has been found particularly advantageous in that it eliminates the tendency of uneven flow of cooling water, insures a uniform flow of cooling water of uniform temperature from side to side and end to end of both the lower and upper quench blocks and eliminates the tendency of forming air pockets in the cooling water channels of the blocks thereby insuring uniform cooling from side to side and end to end of the quench blocks. Formation of air pockets in the cooling water channels immediately results in a change or variation in the temperature of the blocks and consequently in the temperature of the strip material being quenched between the blocks. This condition is undesirable and tends to distort the shape of the strip material.

In preparing the quench block for operation, the bottom block 16 and bottom half 60 of the entry guide are arranged on the clamping bracket 8 and clamped in place by means of the screws 14. The tungsten carbide plates 36 are coated lightly on their underside with graphite grease or other lubricant and slid under pressure into place. The surfaces of the tungsten carbide plates and the block 16 are so nearly flat that the plates will adhere to the block. Tungsten carbide plates 28, 29 and 30 are positioned in the same manner with graphite grease on their underside and the steel blocks 32 and shims 34 are added to fill the remaining space in the channel 20 and thus position the plates in the desired position. The steel strip S to be hardened is pulled through the muffle tube 4 between the entry guide plates 66 which are spaced apart a distance slightly greater than the width of strip S and then over plates 29 and 36 and out of the quench block. The bottom block 16 with the bottom half 60 of the entry guide are then adjusted so that the strip S coming from the muffle tube 4 will be in alignment with the openings between plates 64 and between plates 28 and 30. The four pieces of steel strip 38 are then positioned as shown on the tungsten carbide plates 36. The tungsten carbide plates 40 and 42 are then placed on top of the strip S. The upper block 18 and the upper half 68 of the entry guide are placed on top of the tungsten carbide plates 42 and 66, respectively. The cooling water supply and return are then connected to the upper and lower blocks 16 and 18. Asbestos 72 is packed between the muffle tube 4 and the entry guide and between the two parts of the entry guide. The quench block is

then ready for operation and the heat treating line is started in operation. As the strip passes between the tungsten carbide blocks 29 and 40 it is relatively soft but it will not be scratched since the tungsten carbide blocks are smooth and there is very little pressure on the strip, since the only pressure is due to the weight of the upper tungsten carbide block 40. As the strip S passes between the plates 36 and 42 heat is extracted therefrom and transferred to the cooling water. The use of the lubricant beneath the plates 36 causes the plates to adhere closely to the bottom block 16 and fills all the minute voids which would otherwise exist due to imperfections in the surfaces, thus transmitting heat over substantially 100% of the bottom area of the tungsten carbide plates.

In the embodiment of my invention shown in Figures 12 to 14, plates 28, 29, 30 and 40, fillers 32, and shims 34 of the first embodiment are replaced by a single guide plate 111 having a slot 112 in its top surface through which the strip S is passed, thus guiding and holding it in the center of the quench blocks 16 and 18. The slot 112 is preferably slightly wider than strip S. This guide plate is made of any suitable hard wearing material such as tungsten carbide and may be positioned in the channel 20 with a sliding fit. When quenching relatively thin strip such as .002 inch thick the front face of the plate 111 is preferably flush with the entry end of the block 16. When quenching relatively thick strip such as .012 inch or greater the plate 111 is placed two or three inches from the entry end of the block 16, as shown, thus providing a space 114, the purpose of which will be explained later. The thickness of the guide plate 111 beneath the slot 112 is no greater than and is preferably less than the thickness of the plates 36. The overall thickness of the guide plate 111 is slightly less than the thickness of the plates 36 and 42 plus the thickness of strip S so that the guide plate 111 can slide freely in the channel 20 up against the ends of the adjacent plates 36 and 42. The guide plate 111 is coated slightly on its underside with graphite, grease or similar lubricant so that it can slide freely in and at the same time adhere to the bottom of the channel 20. It will be noted that the block 40 is omitted in this embodiment. When using the guide plate 111 the entry guides 60 and 68 may be omitted if desired in which case the quench blocks are abutted against the exit end of the furnace muffle tube 4.

In preparing the quench blocks for operation the strip S to be hardened is pulled through the muffle tube 4, through the open space 114, through the slot 112, over the plates 36 and out of the quench block. When the strip S is narrow four pieces of steel strip 38 are then positioned on each of the four corners of the tungsten carbide plates 36 and the tungsten carbide plates 42 are placed on top of the strip S. The upper block 18 is then placed on top of the tungsten carbide plate 42. The cooling water supply and return pipes are then connected to the upper and lower blocks 16 and 18 and the parts are packed with asbestos after which the apparatus is ready for operation.

In quenching relatively wide strip the steel strips 38 may be omitted since the tungsten carbide plates 42 will be only slightly wider than the strip S and will always lie flat thereagainst without tilting. When the guide plate 111 is spaced from the entry end of the block 16 the chamber 114 is filled with neutral atmosphere gas or other

gas from the furnace so as to exclude air from the space. The chamber 114 permits prequenching of the strip S before it is thoroughly quenched between the tungsten carbide plates 36 and 42.

When the heat treating line using this embodiment of my invention is started, the relatively soft strip S passes through the slot 112 without being scratched because the slot is smooth and there is no pressure on the strip at this point. As the strip passes between the plates 36 and 42 heat is extracted therefrom and is transferred to the cooling water in the same way as in the first embodiment.

While several embodiments of my invention have been shown and described it will be apparent that other adaptations and modifications may be made without departing from the scope of the following claims.

I claim:

1. A quench block for continuously quenching steel strip comprising a bottom block, three guide plates of hard wearing material arranged side by side on the top of said lower block at the entry end thereof, the middle plate being of less thickness than the outer plates and the thickness of the outer plates being equal, a hard wearing strip of at least the same thickness as the middle plate arranged on top of said bottom block adjacent the entry plates, an upper hard wearing strip mounted above the first named hard wearing strip, the thickness of the outer guide plates being less than the sum of the thicknesses of the upper and lower hard wearing strips and the steel strip being quenched therebetween, a top block resting on said upper hard wearing strip, and means for cooling said top and bottom blocks.

2. A quench block according to claim 1 including a bottom entry guide fastened to said bottom block, said bottom entry guide having spaced apart longitudinal slots in its upper surface, a plate of hard wearing material in each longitudinal slot extending above the top of said bottom entry guide, and a top entry guide having spaced apart longitudinal slots in its lower surface for receiving said last named plates.

3. A quench block for continuously quenching steel strip comprising a bottom block, three plates of hard wearing material arranged side by side on the top of said lower block at the entry end thereof, the middle plate being of less thickness than the outer plates and the thickness of the outer plates being equal, a hard wearing strip of the same thickness as the middle plate arranged on top of said bottom block adjacent the entry plates, an upper plate of hard wearing material mounted above said middle plate between the outer plates and extending thereabove when a strip is in the quench block, an upper hard wearing strip having a thickness greater than the last named plate mounted above the first named hard wearing strip, and a top block resting on said upper hard wearing strip, said top and bottom blocks each having a plurality of longitudinal cooling passageways therein and manifolds at each end connecting said passageways.

4. A quench block according to claim 3 including a bottom entry guide fastened to said bottom block, said bottom entry guide having spaced apart longitudinal slots in its upper surface, a plate of hard wearing material in each longitudinal slot extending above the top of said bottom entry guide, and a top entry guide having

spaced apart longitudinal slots in its lower surface for receiving said last named plates.

5. A quench block for continuously quenching steel strip comprising a bottom block, three plates of hard wearing material arranged side by side on the top of said lower block at the entry end thereof, the middle plate being of less thickness than the outer plates and the thickness of the outer plates being equal, a hard wearing strip of the same thickness as the middle plate arranged on the top of said bottom block adjacent the entry plates, a lubricant between the hard wearing material and the bottom block, spacers resting on the hard wearing strip at the corners thereof, said spacers being of substantially the same thickness as the steel strip being quenched, an upper plate of hard wearing material mounted above said middle plate between the outer plates and extending thereabove when a strip is in the quench block, an upper hard wearing strip having a thickness greater than the last named plate mounted above the first named hard wearing strip, a top block resting on said upper plate, and means for cooling said top and bottom blocks.

6. A quench block according to claim 5 including a bottom entry guide fastened to said bottom block, said bottom entry guide having spaced apart longitudinal slots in its upper surface, a plate of hard wearing material in each longitudinal slot extending above the top of said bottom entry guide, and a top entry guide having spaced apart longitudinal slots in its lower surface for receiving said last named plates.

7. A quench block for continuously quenching steel strip comprising a bottom block, three plates of hard wearing material arranged side by side on the top of said lower block at the entry end thereof, the middle plate being of less thickness than the outer plates and the thickness of the outer plates being equal, a hard wearing strip of the same thickness as the middle plate arranged on the top of said bottom block adjacent the entry plates, a lubricant between the hard wearing material and the bottom block, spacers resting on the hard wearing strip at the corners thereof, said spacers being of substantially the same thickness as the steel strip being quenched, an upper plate of hard wearing material mounted above said middle plate between the outer plates and extending thereabove when a strip is in the quench block, an upper hard wearing strip having a thickness greater than the last named plate mounted above the first named hard wearing strip, a top block resting on said upper hard wearing strip, said top and bottom blocks each having a plurality of longitudinal cooling passageways therein and manifolds at each end connecting said passageways.

8. A quench block according to claim 7 including a bottom entry guide fastened to said bottom block, said bottom entry guide having spaced apart longitudinal slots in its upper surface, a plate of hard wearing material in each longitudinal slot extending above the top of said bottom entry guide, and a top entry guide having spaced apart longitudinal slots in its lower surface for receiving said last named plates.

9. A quench block for continuously quenching narrow steel strip comprising a bottom block having a longitudinal channel in the top surface thereof, longitudinal side plates along the sides of said lower block extending above the top thereof, three tungsten carbide plates arranged side by side in said channel at the entry end thereof, the middle tungsten carbide plate being

of less thickness than the outer tungsten carbide plates and the thickness of the outer tungsten carbide plates being equal, tungsten carbide means of the same thickness as the middle tungsten carbide plate arranged in said channel adjacent the entry tungsten carbide plates, a lubricant between the tungsten carbide and the bottom of said channel, spacers resting on the tungsten carbide means at the corners thereof, 10 said spacers being of substantially the same thickness as the steel strip being quenched, an upper tungsten carbide plate mounted above said middle tungsten carbide plate between the outer tungsten carbide plates and extending thereabove when a strip is in the quench block, upper tungsten carbide means having a thickness greater than the last named tungsten carbide plate mounted above the first named tungsten carbide, a top block resting on said upper tungsten carbide means, 15 an end plate fastened to the exit end of said bottom block and extending upwardly therefrom to prevent longitudinal movement of said upper block, and means for cooling said top and bottom blocks.

10. A quench block according to claim 9 including a bottom entry guide fastened to said bottom block, said bottom entry guide having spaced apart longitudinal slots in its upper surface, a tungsten carbide plate in each longitudinal slot 20 extending above the top of said bottom entry guide, and a top entry guide having spaced apart longitudinal slots in its lower surface for receiving said last named tungsten carbide plates.

11. A quench block for continuously quenching 25 narrow steel strip comprising a bottom block having a longitudinal channel in the top surface thereof, longitudinal side plates along the sides of said lower block extending above the top thereof, three tungsten carbide plates arranged 30 side by side in said channel at the entry end thereof, the middle tungsten carbide plate being of less thickness than the outer tungsten carbide plates and the thickness of the outer tungsten carbide plates being equal, tungsten carbide 35 means of the same thickness as the middle tungsten carbide plate arranged in said channel adjacent the entry tungsten carbide plates, a lubricant between the tungsten carbide and the bottom of said channel, spacers resting on the tungsten carbide means at the corners thereof, said spacers 40 being of substantially the same thickness as the steel strip being quenched, an upper tungsten carbide plate mounted above said middle tungsten carbide plate between the outer tungsten carbide plates and extending thereabove when 45 a strip is in the quench block, upper tungsten carbide means having a thickness greater than the last named tungsten carbide plate mounted above the first named tungsten carbide means, a top block resting on said upper tungsten carbide means, 50 and an end plate fastened to the exit end of said bottom block and extending upwardly therefrom to prevent longitudinal movement of said upper block, said top and bottom blocks having 55 a plurality of longitudinal cooling passageways therein and manifolds at each end connecting said passageways.

12. A quench block for continuously quenching 60 steel strip comprising a bottom block, a guide plate of hard wearing material positioned on the top of said bottom block adjacent the entry end thereof, said guide plate having a slot in its top surface slightly wider than the width of the strip being quenched, a hard wearing strip arranged 65 on top of said bottom block adjacent the said

9.

guide plate, said hard wearing strip having a thickness at least equal to the thickness of the slotted portion of the said guide plate, an upper hard wearing strip mounted above the first named hard wearing strip, the thickness of the said guide plate being less than the sum of the thicknesses of the upper and lower hard wearing strips and the steel strip being quenched therebetween, a top block resting on said upper hard wearing strip, and means for cooling said top and bottom blocks.

13. A quench block for continuously quenching steel strip comprising a bottom block, a guide plate of hard wearing material positioned on the top of said bottom block adjacent the entry end thereof, said guide plate having a slot in its top surface slightly wider than the width of the strip being quenched, a hard wearing strip arranged on top of said bottom block adjacent the said guide plate, said hard wearing strip having a thickness at least equal to the thickness of the slotted portion of the said guide plate, an upper hard wearing strip mounted above the first named hard wearing strip, the thickness of the said guide plate being less than the sum of the thicknesses of the upper and lower hard wearing strips and the steel strip being quenched therebetween, a top and bottom blocks each having a plurality of longitudinal cooling passageways therein and manifolds at each end connecting said passageways.

14. A quench block for continuously quenching steel strip comprising a bottom block, a guide plate of hard wearing material positioned on the top of said lower block adjacent the entry end thereof, said guide plate having a slot in its top surface slightly wider than the width of the strip being quenched, a hard wearing strip arranged on top of said bottom block adjacent the said guide plate, said hard wearing strip having a thickness at least equal to the thickness of the slotted portion of the said guide plate, a lubricant between the hard wearing material and the bottom block, spacers resting on the hard wearing strip at the corners thereof, said spacers being of substantially the same thickness as the steel strip being quenched, an upper hard wearing strip mounted above the first named hard wearing strip, the thickness of the said guide plate being less than the sum of the thicknesses of the upper and lower hard wearing strips and the steel strip being quenched therebetween, a top block resting on said upper hard wearing strip, and means for cooling said top and bottom blocks.

15. A quench block for continuously quenching steel strip comprising a bottom block, a guide plate of hard wearing material positioned on the top of said lower block adjacent the entry end thereof, said guide plate having a slot in its top surface slightly wider than the width of the strip being quenched, a hard wearing strip arranged on top of said bottom block adjacent the said guide plate, said hard wearing strip having a thickness at least equal to the thickness of the slotted portion of the said guide plate, a lubricant between the hard wearing material and the bottom block, spacers resting on the hard wearing strip at the corners thereof, said spacers being of substantially the same thickness as the steel strip being quenched, an upper hard wearing strip mounted above the first named hard wearing strip, the thickness of the said guide plate being less than the sum of the thicknesses of the upper and lower hard wearing strips and the steel strip being quenched therebetween, a top block resting on said upper hard wearing strip, said top and bottom blocks each having a plurality of longitudinal cooling passageways therein and manifolds at each end connecting said passageways.

10.

bottom blocks, each having a plurality of longitudinal cooling passageways therein and manifolds at each end connecting said passageways.

16. A quench block for continuously quenching steel strip comprising a bottom block having a longitudinal channel in the top surface thereof, longitudinal side plates along the sides of said bottom block extending above the top thereof, a tungsten carbide guide plate positioned in the said channel adjacent the end thereof, said guide plate having a slot in its top surface slightly wider than the width of the strip being quenched, tungsten carbide means arranged in said channel adjacent the said guide plate, said tungsten carbide means having a thickness at least equal to the thickness of the slotted portion of the said guide plate, a lubricant between the tungsten carbide and the bottom of said channel, spacers resting on the tungsten carbide means at the corners thereof, said spacers being of substantially the same thickness as the steel strip being quenched, upper tungsten carbide means mounted above the first named tungsten carbide means, the thickness of the said guide plate being less than the sum of the thicknesses of the upper and lower tungsten carbide means and the steel strip being quenched therebetween, a top block resting on said upper tungsten carbide means, an end plate fastened to the exit end of said bottom block and extending upwardly therefrom to prevent longitudinal movement of said upper block, and means for cooling said top and bottom blocks.

17. A quench block for continuously quenching steel strip comprising a bottom block having a longitudinal channel in the top surface thereof, longitudinal side plates along the sides of said bottom block extending above the top thereof, a tungsten carbide guide plate positioned in the said channel adjacent the end thereof, said guide plate having a slot in its top surface slightly wider than the width of the strip being quenched, tungsten carbide means arranged in said channel adjacent the said guide plate, said tungsten carbide means having a thickness at least equal to the thickness of the slotted portion of the said guide plate, a lubricant between the tungsten carbide and the bottom of said channel, spacers resting on the tungsten carbide means at the corners thereof, said spacers being of substantially the same thickness as the steel strip being quenched, upper tungsten carbide means mounted above the first named tungsten carbide means, the thickness of the said guide plate being less than the sum of the thicknesses of the upper and lower tungsten carbide means and the steel strip being quenched therebetween, a top block resting on said upper tungsten carbide means, an end plate fastened to the exit end of said bottom block and extending upwardly therefrom to prevent longitudinal movement of said upper block, said top and bottom blocks each having a plurality of longitudinal cooling passageways therein and manifolds at each end connecting said passageways.

18. A quench block for continuously quenching steel strip comprising a bottom block, guide means of hard wearing material positioned on top of said bottom block adjacent the entry end thereof, said guide means having a relatively thin portion slightly wider than the width of the strip being quenched and relatively thick portions on each side of the thin portion, a hard wearing strip of at least the same thickness as the thin portion of the guide means arranged

on top of said bottom block adjacent the guide means, an upper hard wearing strip, the thickness of said thick portions of the guide means being less than the sum of the thicknesses of the upper and lower hard wearing strips and the steel strip being quenched therebetween, a top block resting on said upper hard wearing strip, and means for cooling said top and bottom blocks.

19. A quench block for continuously quenching steel strip comprising a bottom block, guide means of hard wearing material positioned on top of said bottom block adjacent the entry end thereof, said guide means having a relatively thin portion slightly wider than the width of the strip being quenched and relatively thick portions on each side of the thin portion, a hard wearing strip of at least the same thickness as the thin portion of the guide means arranged on top of said bottom block adjacent the guide means, a lubricant between the hard wearing material and the bottom block, spacers resting on the hard wearing strip at the corners thereof, said spacers being of substantially the same thickness as the steel strip being quenched, an upper hard wearing strip mounted on said spacers, the thickness of said thick portions of the guide means being less than the sum of the thicknesses of the upper and lower hard wearing strips and the steel strip being quenched therebetween, a top block resting on said upper hard wearing strip, said top and bottom blocks each having a plurality of longitudinal cooling passageways therein and manifolds at each end connecting said passageways.

20. A quench block for continuously quenching steel strip comprising a bottom block having a longitudinal channel in the top surface thereof, longitudinal side plates along the sides of said bottom block extending above the top thereof, tungsten carbide guide means positioned in the said channel adjacent the entry end thereof, said guide means having a relatively thin portion slightly wider than the width of the strip being quenched and relatively thick portions on each side of the thin portion, tungsten carbide means of at least the same thickness as the thin portion of the guide means arranged in said channel adjacent the guide means, a lubricant between the tungsten carbide and the bottom of said channel, spacers resting on the tungsten carbide means at the corners thereof, said spacers being of substantially the same thickness as the steel strip being quenched, upper tungsten carbide means mounted on said spacers above the first named tungsten carbide means, the thickness of said thick portions of the guide means, being less than the sum of the thicknesses of the upper and lower tungsten carbide means and the steel strip being quenched therebetween, a top block resting on said upper tungsten carbide means, an end plate fastened to the exit end of said bottom block and extending upwardly therefrom to prevent longitudinal movement of said upper block, said top and bottom blocks each having a plurality of longitudinal cooling passageways therein and manifolds at each end connecting said passageways.

21. A quench block for continuously quenching steel strip comprising a bottom block, strip supporting means of hard wearing material positioned on top of said bottom block, said bottom

block having a transverse manifold adjacent each end and a plurality of longitudinal spaced apart parallel passageways extending between said manifolds, a hard wearing strip above said strip supporting means, a top block resting on said hard wearing strip, said top block having a transverse manifold adjacent each end and a plurality of longitudinal spaced apart parallel passageways extending between said manifolds, and means for delivering a coolant to the manifolds at one end of said blocks.

22. A quench block for continuously quenching narrow steel strip comprising a bottom block having a longitudinal channel in the top surface thereof, longitudinal side plates along the sides of said lower block extending above the top thereof, strip supporting means of hard wearing material positioned in said channel, said bottom block having a transverse manifold adjacent each end and a plurality of longitudinal spaced apart parallel passageways extending between said manifolds, a hard wearing strip above said strip supporting means, a top block resting on said hard wearing strip between said side plates, said top block having a transverse manifold adjacent each end and a plurality of longitudinal spaced apart parallel passageways extending between said manifolds, an end plate fastened to the exit end of said bottom block and extending upwardly therefrom to prevent longitudinal movement of said upper block, and means for delivering a coolant to the manifolds at one end of said blocks.

23. A quench block for continuously quenching steel strip comprising a bottom block, said bottom block having a transverse manifold adjacent each end and a plurality of longitudinal spaced apart parallel passageways extending between said manifolds, guide means of hard wearing material positioned on top of said bottom block adjacent the entry end thereof, said guide means having a relatively thin portion slightly wider than the width of the strip being quenched and relatively thick portions on each side of the thin portion, a hard wearing strip of at least the same thickness as the thin portion of the guide means arranged on top of said bottom block adjacent the guide means, an upper hard wearing strip, the thickness of said thick portions of the guide means being less than the sum of the thicknesses of the upper and lower hard wearing strips and the steel strip being quenched therebetween, a top block resting on said upper hard wearing strip, said top block having a transverse manifold adjacent each end and a plurality of longitudinal spaced apart parallel passageways extending between said manifolds, and means for delivering a coolant to the manifolds at one end of said blocks.

JULIUS HARASTY.
